Primary Examiner — Philip S Hyder(74) *Attorney, Agent, or Firm* — Che-Yang Chen; Law Office of Michael Chen(57) **CLAIM**

The ornamental design for a double bowl bead spinner, as shown and described.

DESCRIPTION

FIG. 1 is a perspective view of the double bowl bead spinner showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view thereof when the double bowl bead spinner is open.

The broken lines shown in the drawings represent portions of the double bowl bead spinner that form no part of the claimed design.
